United States Patent Office

Des. 182,072
Patented Feb. 11, 1958

182,072

TRUCK

Charles M. Jordan, Birmingham, and Luther W. Stier, Rochester, Mich., assignors to General Motors Corporation, Detroit, Mich., a corporation of Delaware

Application December 29, 1955, Serial No. 39,513

Term of patent 7 years

(Cl. D14—3)

Fig. 1 is a side elevation of a truck embodying our new design;

Fig. 2 is a top plan view thereof;

Fig. 3 is a front view of the truck; and

Fig. 4 is a rear view of the truck.

The dominant features of our design reside in those portions shown in full lines.

We claim:

The ornamental design for a truck, substantially as shown and described.
